Henry S. Brewington

UNITED STATES PATENT OFFICE.

HENRY S. BREWINGTON, OF BALTIMORE, MARYLAND.

PAPER CONTAINER.

1,425,168.

Specification of Letters Patent. Patented Aug. 8, 1922.

Application filed April 26, 1921. Serial No. 464,765.

To all whom it may concern:

Be it known that I, HENRY S. BREWINGTON, a citizen of the United States, residing at Baltimore city, State of Maryland, have 5 invented certain new and useful Improvements in Paper Containers, of which the following is a specification.

This invention relates to receptacles which are constructed of paper, pasteboard or 10 analogous material, and more particularly to receptacles of this kind which are cylindrical in shape.

The invention has for its object to provide novel and improved closures for the ends of 15 the receptacle, the same consisting in a combination and arrangement of parts to be hereinafter described and claimed.

In order that the invention may be better understood, reference is had to the accompanying drawing forming a part of this 20 specification, and in said drawing—

Figure 1 is a central vertical section of the receptacle;

Fig. 2 is a plan view thereof, and

Fig. 3 is a vertical section of the bottom 25 portion of a receptacle showing a modified structure.

Referring specifically to the drawing, 5 denotes the cylindrical wall of the receptacle, 30 the same being provided with end closures in the form of disks 6 and 7, respectively, the former being at the top and the latter at the bottom. These disks may be made of the same material as that of which the 35 cylinder 5 is made.

To the top of the cylinder 5, on the outside thereof, is permanently secured by any suitable means, an encircling band or ring 8 composed of the same material as that of 40 the cylinder. This band projects a short distance above the top edge of the cylinder so that it may enclose the disk 6, the latter seating on the top edge of the cylinder. The structure results in an annular shoulder 45 inside the cylinder, said shoulder forming a seat for the disk 6.

In order to secure the disk 6 in place and also to seal the same, there is folded over the top edge of the band 8 a rigid sheet metal 50 ring 9 which extends downwardly inside the band, in contact with the inner surface thereof, as shown at 10, and has adjacent to the top of the disk an inturned flange 11, said

flange being continuous and annular, and engaging the top of the disk where it seats 55 on the top edge of the cylinder 5. The flange 11 is pressed down on the disk to hold the same firmly seated. The parts 10 and 11 also securely seal the joint between the edge of the disk and the inner surface of the band 60 8 against which said edge contacts. The folded outer portion of the ring 9 is pressed together to tightly grip the band 8, the inner portion 10 is firmly pressed into contact with the inner surface of the band 8, and the 65 flange 11 is tightly pressed down against the marginal portion of the disk 6, in view of which it will be evident that the disk is securely held in place, and also sealed to prevent leakage of the contents of the receptacle if such contents are of a liquid 70 nature. The ring can be spun on or applied in any other approved manner, and the structure is very simple and cheap, and readily assembled.

The bottom disk 7 is secured and sealed in the same manner as the top disk 6. However, the sealing and securing ring 12 is clamped over the bottom edge of the cylinder 5, and has a portion 13 extending upwardly thereinto in contact with the inner surface thereof, and terminating in an in-turned annular flange 14 on which the disk 7 seats.

Fig. 3 shows a modified bottom disk 7^a, the 85 same having its marginal portion slightly elevated, as shown at 7^b to form a shoulder 7^c located inwardly of the edge of the disk and concentric therewith. The flange 14 engages the bottom of the raised portion 7^b of 90 the disk, and extends inwardly far enough to abut with its edge against the shoulder 7^c. This structure provides a double seal for the receptacle bottom, and effectually prevents leakage.

The rings 9 and 12 also act to reinforce and stiffen to body 5 of the receptacle so that it will retain its cylindrical shape under rough handling, and prevent the top and bottom closures from getting loose to rupture the sealing contact.

I claim:

A paper receptacle comprising a cylindrical body, an end closure for said body comprising a disk inside the same and having 105 its edge in contact with the inner surface

of the body, and a sealing and securing member for the disk comprising a rigid metallic ring extending over and secured to the edge of the body, and having an inner portion extending into the body in intimate contact with its inner surface, said inner portion terminating in an annular flange which engages the disk, and the inner por-

tion and its flange covering the joint between the edge of the disk and the body of the receptacle, the disk having an annular shoulder concentric with its edge against which shoulder the edge of the flange has a sealing contact. 10

In testimony whereof I affix my signature. 15
HENRY S. BREWINGTON.
